UNITED STATES PATENT OFFICE.

THOMAS W. BELL AND THOMAS C. ROGERS, OF SISTERSVILLE, WEST VIRGINIA.

WIRE-LINE CLAMP.

1,308,924.

Specification of Letters Patent.

Patented July 8, 1919.

Application filed October 21, 1918. Serial No. 259,010.

To all whom it may concern:

Be it known that we, THOMAS W. BELL and THOMAS C. ROGERS, citizens of the United States, residing at Sistersville, in the county of Tyler, State of West Virginia, have invented a new and useful Wire-Line Clamp, of which the following is a specification.

The device forming the subject matter of this application is adapted to be used for gripping cables of the kind used in well drilling, and one object of the invention is to improve generally and to enhance the utility of devices of the kind above mentioned.

Another object of the invention is to supply a novel link construction, holding the jaws together pivotally, and affording great strength.

Another object of the invention is so to construct a device of the class above mentioned, that the same will have great gripping power and long leverage in engaging the cable.

A further object of the invention is to provide novel means for holding the grips in the jaws.

The invention contemplates the provision of means whereby the link may be set free, to afford some play, when the jaws are open.

But one form of the invention is shown in the drawings, and it is to be understood that, within the scope of what is claimed, a mechanic may make changes without departing from the spirit of the invention.

In the accompanying drawings:—

Figure 1 shows in rear elevation, a device constructed in accordance with the invention; Fig. 2 is a front elevation; Fig. 3 is a side elevation; Fig. 4 is a section on the line 4—4 of Fig. 3; Fig. 5 is a fragmental perspective showing parts of one of the jaws; and Fig. 6 is a perspective disclosing the retainer which holds the grip in the jaw.

In carrying out the invention there is provided a pair of jaws 1 provided with hooks 26 at their upper ends, the hooks being adapted to receive the usual hoisting rings 27. In the inner edges of the jaws 1, dovetailed recesses 2 are formed, and into the recesses 2, renewable grips 3 may be slid transversely, the grips being grooved longitudinally as shown at 4, to receive the cable 5 wherewith the structure is adapted to coöperate. The jaws 1 are supplied upon

their rear sides with transverse ribs 6 which project beyond the bases of the recesses 2 and serve to prevent the grips 3 from sliding rearwardly out of the recesses. The inner ends of the ribs 6 are loosely united by means of pivot elements 7.

The jaws 1 are provided with rearwardly extended lugs 8 which project, as shown at 9 in Fig. 5 beyond the bases of the recesses 2 and aid in holding the grips 3 in the recesses 2, against rearward movement. Arms 10 project forwardly from the jaws 1 and are supplied with seats or notches 11. Angular retainers 12 are provided, the same including, each, a transverse part 14 and a longitudinal part 15. The transverse parts 14 of the retainers 12 rest on top of the arms 10, the longitudinal parts 15 of the retainers being received in the seats or notches 11, and engaging the forward edges of the grips 3 to prevent the grips from moving forwardly. The grips 3, therefore, are held in the dovetailed recesses 2, without the use of set screws or like devices, but, by removing the retainers the grips 3 may be renewed at any time. The parts 14 of the retainers 12, and the arms 10 are supplied with openings 16, adapted to receive securing devices 17, whereby the retainers 12 are held on the arms, in a way which will be understood clearly when Figs. 4, 3 and 2 are examined.

The rearwardly extended lugs 8 are surrounded by a continuous loop-shaped link 18, the lugs having projections 19 which co-operate with the link to hold the link on the lugs. The link 18 is equipped with rearwardly extended ears 20, having curved or eccentric outer edges, coacting with the projections 19.

The forward ends of the arms 10 are received within a U-shaped yoke 21, the ends of the arms of the yoke being united by a pivot element 22, with one of the arms 10, the said arm being broadened as shown at 23 for the sake of reinforcement. A screw or like operating member 24 is mounted in the end of the yoke 21 and engages with other arm 10 as shown in Fig. 2, the screw 24 having a turning head 25, of any desired sort.

Let it be supposed that the parts are arranged as shown in Fig. 4. Then the lugs 8 are fulcrumed on the link 18, the projections 19 being engaged with the curved outer edges of the ears 20 so as to hold the link 18 in place against the jaws 1. The screw

24 is advanced, the outer ends of the arms 10 are pressed toward each other, and the cable 5 is held securely between the grips 3. In this connection it should be stated that, 5 during the operation of gripping the cable 5, none of the strain is carried by the pivot elements 7 which united the ribs 6, the ribs, and consequently the jaws 1 being pivotally united merely for the purpose of holding the jaws 10 in proper relation to each other during the mounting of the structure on the cable 5. In order to release the hold of the grips 3 on the cable 5, the screw 24 may be retracted and, if desired, the yoke 21 may be swung 15 on the pivot element 22, off that arm where- with the screw coöperates.

Since the link 18 is continuous and loop-shaped, the link will have great strength, and will not open during the gripping operation. When the projections 19 ride on the extended ears 20, the link 3 is held relatively close to the jaws 1, and, consequently, the grips 3 have a strong hold on the cable 5, when the outer ends of the arms 10 are 25 pressed toward each other by the action of the screw 24. As has been stated, the grips 3 may be released for renewal, by removing the angular retainers 12, set screws and the like being rendered unnecessary.

30 Having thus described the invention, what is claimed is:—

1. In a device of the class described, co-operating jaws having rearwardly extended lugs and forwardly extended arms, a continuous loop-shaped link disposed transversely of the lugs and parallel to the jaws, the lugs passing through the link; means on the lugs for retaining the link thereon; and an adjustable tightening device connecting 35 the arms.

2. In a device of the class described, co-operating jaws having rearwardly extended

lugs and forwardly extended arms; a continuous loop-shaped link disposed transversely of the lugs and parallel to the jaws, 45 the lugs passing through the link; means on the lugs for retaining the link thereon, the rear face of the link being provided with eccentric parts coöperating with said means; and a tightening device connecting the arms. 50

3. In a device of the class described, co-operating jaws having recesses in their inner edges, the jaws having rearwardly extended lugs and being provided with forwardly extended arms, the jaws having rearwardly extended ribs projecting beyond the bases of the recesses; removable retainers on the arms; grips in the recesses and held therein by the projecting portions of the ribs and by the retainers; means for pivotally connecting the ribs of the respective jaws; a link receiving the lugs; and a tightening means connecting the arms. 60

4. In a device of the class described, co-operating jaws equipped with recesses in 65 their inner edges, the jaws having rearwardly extended lugs, and being provided with forwardly extended arms, the jaws having rearwardly extended ribs which project beyond the bases of the recesses; removable 70 retainers on the arms; grips in the recesses and held therein by the projecting portions of the ribs and by the retainers; a link receiving the lugs; and a tightening means connecting the arms. 75

In testimony that we claim the foregoing as our own, we have hereto affixed our signatures in the presence of two witnesses.

THOMAS W. BELL.
THOS. C. ROGERS.
